UNITED STATES PATENT OFFICE.

MASCHIL D. CONVERSE, OF NEW YORK, N. Y., ASSIGNOR TO JOHN J. TOWER,
OF SAME PLACE.

PIPE AND NUT WRENCH.

SPECIFICATION forming part of Letters Patent No. 661,011, dated October 30, 1900.

Application filed June 7, 1900. Serial No. 19,368. (No model.)

To all whom it may concern:

Be it known that I, MASCHIL D. CONVERSE, a citizen of the United States, residing at New York, borough of Manhattan, in the county 5 of New York and State of New York, have invented certain new and useful Improvements in Pipe and Nut Wrenches; and I do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 My present invention relates to pipe-wrenches and to combined nut and pipe-wrenches, and more particularly to that class of such tools in which a circumscribing jaw is provided with teeth on the engaging side, 20 the points of which may be described as ranged upon a line or lines curvilinearly eccentric and eccentric divergent to the engaging surface of the arc of another—the fulcrum—jaw, which latter is usually of uniform radii, sometimes 25 also rigid or integral and sometimes revoluble and toothed or smooth. In the practical use of these types of wrenches as heretofore constructed certain annoying difficulties have been encountered which it is the 30 purpose of my present invention to overcome, among which are (a) uncertainty or lack of promptness and uniformity of grip upon pipes or nuts of varying dimensions, within the range of any given size of wrench, (b) 35 liability to slip upon pipe of one dimension in some instances, or (c) to indent or crush the pipe of other dimensions, and (d) to become "jammed" or "bound" upon the same in other cases, so that in consequence it has 40 not been possible to operate such wrenches with confidence and uniform and unfailing facility. The two first-named difficulties (a, b) are manifestly bound to occur if the convergence of the line-of-the-teeth points of the 45 teeth on the circumscribing jaw is inconstant or of unequal degree with respect to the engaging surface (or line-of-the-teeth points) of the fulcrum-jaw and whether the latter be rigid or smooth, and the third (c) and fourth 50 named (d) difficulties will occur when, combined with such inconstant convergence, the degree of convergence is too low or acute and

whether, as stated, the fulcrum-jaw be rigid and smooth or revoluble and toothed or smooth, a too low or too acute angle of convergence, in any case causing the pipe to be impinged by the respective jaws at points too nearly approximating the exact diametral sides, as will be clearly understood by those skilled in the art on examination of the accompanying drawings. This statement of fact respecting the state of the art is furthermore based upon extended practical tests and experimental observation of known forms of the type of tools referred to when applied to either 65 old or new work in which the ordinary gas, steam, and hydraulic pipe of commerce has been employed and with the express purpose of ascertaining the defects in such wrenches, the causes for their unsatisfactory operation, 70 and of devising means for overcoming the same.

To this end my present invention consists in, first, constructing pipe-wrenches of the class described so that the points of the teeth 75 on the circumscribing jaw shall be ranged on a true involute line, the evolute of which is concentric to the engaging arc of the fulcrum-jaw, and, second, which evolute shall be of such diameter as to insure in manufacture any proper predetermined degree of convergence of the involute line relatively the 80 said engaging arc surface of the fulcrum-jaw that the uses of the tool may demand, which for ordinary metal pipe may not be, however, 85 I have discovered, less than eleven degrees nor greater than fifteen degrees; third, in constructing the perpendicular side of the respective teeth on the circumscribing jaw tangential to the evolute and orderly graduating 90 and differentiating the spacing of the same, for purposes hereinafter shown, and, fourth, in a certain specific provision for preventing crushing of very thin pipe when it is desirable or necessary to use the tool on the same, 95 and in other certain particulars of combination of all these, all of which will be herein-after fully set forth and claimed. By means of my said improvements a pipe-wrench of this type may also be readily used for turning square or hexagonal nuts, as will be seen.

In some cases tools of the class to which my invention relates have been constructed with a smooth or with a serrated (toothed)

pivoted support or fulerum-jaw. In my present invention I dispense with these and employ only a smooth rigid (preferably integral) fulerum-jaw constructed, preferably, with uniform radii, though it may be of involute form, as will be clearly understood; but in the case of very thin pipe (more properly tubing) I sometimes employ a toothless or smooth-surfaced concave-recessed striding fulerum-jaw 5 piece removably pivoted to the rigid fulerum-bearing concentrically. Effort has been made (with obvious error) to overcome the tendency of such wrenches to "jam" or "bind" the pipe between the rigid jaws thereof by 10 making a straight plane surface (instead of an arc form) upon the fulerum-jaw. Such form, as will be seen, I cannot successfully employ. My present invention, furthermore, operating successfully fulfils the original objects 15 for which this type of tool was designed—viz., a wide range within small compass.

In the drawings, Figure 1 is a side elevation of my invention, showing the manner of 20 its construction, the relation of its various parts and their form, and also illustrating its operation in part, as well as certain other matters hereinafter referred to. Fig. 2 is a similar view, partly sectional, showing a specific construction as to a part of my invention, also certain other matters hereinafter referred to. Fig. 3 is a cross-sectional view 25 of a portion of Fig. 2, hereinafter referred to. Figs. 4, 5, and 6 are diagrammatical representations of right and wrong relations between the impinging surfaces of pipe-wrenches of the class my invention relates to, hereinafter particularly referred to. Figs. 7 and 8 are precisely similar side elevations of my invention, showing its adaptation as a nut-wrench, 30 all of which will be hereinafter more fully described in detail.

Like letters indicate corresponding parts throughout the drawings.

45 A is what I term the "involute jaw," B the fulerum-jaw, and C the handle, of the wrench. *aa* are graduated differentially-spaced teeth on the jaw A, with the points of each ranged upon an involute line represented by the dotted line *b b*, traced in the well-known way from the evolute, which is represented by the dotted circle *c*. To lay out or determine the proper graduation and differential spacing of the teeth *aa* and for other purposes, a semi-circle *d d*, (shown in dotted lines, Fig. 1,) of uniform radii, concentric to the jaw B, is drawn at any point beyond the inner face of the jaw A, and straight lines tangential to the evolute *c* are drawn to points *e e e*, equidistant from each other on said line *d d*, and a tooth-point is then located at each intersection thereof with said involute line *b b*, the perpendicular side *f f* of the teeth respectively coinciding with said tangential lines, so as to be tangent 50 to said evolute. Now the line *b b*, being a true evolute, converges at a uniform degree relatively the engaging surface *g* of the ful-

erum-jaw B, so that it follows that the teeth *a a* will be uniformly graduated and differential.

70 B' in Figs. 2 and 3 is a removable pivoted fulerum-jaw or striding piece mounted in a slot *j* in the fulerum B on the pin *h* and provided with one or more smooth-surfaced or toothless concave recesses *i i* in order to present a greater surface contact on smaller pipe, as at *r*, or two points of contact on larger pipe, as at *s s*, and to be used as hereinafter explained.

75 In order that the potency and operation of my present improvements may be more clearly understood, I have shown diagrammatically by Figs. 4, 5, and 6 a comparison of the same and known forms of this type of wrenches. In these diagrams, *g'* represents the engaging surface (*g*) of the fulerum-jaw B; *b' b'*, the involute line (*b*) of jaw A of my invention as they would appear straightened out, illustrating the constant degree of convergence thereof, which (degree) throughout 80 the drawings is about twelve and one-half degrees, as may be seen by laying a protractor upon the dotted lines *o' o' o'* of the diagrams, (which lines correspond to dotted line *o* of Fig. 1.) In diagram Fig. 5 line *k' k'* is the eccentric dotted line *k k* of Fig. 1 straightened out, illustrating the inefficiency of such a line for the points of the teeth of the circumscribing jaw A to be ranged upon, and in diagram Fig. 6 lines *l' l'* and *m' m'* are, respectively, 85 the two eccentric dotted lines *l l* and *m m* (that cross each other at *n*) of Fig. 2 straightened out, also illustrating the inefficiency of such combination of eccentric lines for the points of the teeth of the circumscribing jaw A to 90 be ranged upon, both which (*k' k'* and *l' l'* and *m' m'*) represent the construction heretofore practiced.

95 Those skilled in the art will see that my invention provides a uniform or constant angle of convergence for the line of the teeth-points on the circumscribing jaw A with relation to the fulerum-jaw B, as shown, which can only be done by making said line-of-the-teeth points a true involute, and not by use 100 of an eccentric or combination or succession of eccentric lines, as heretofore, and consequently, as shown in Figs. 1 and 2 and in diagram Fig. 4, pipes of different diameters are impinged (*q' q' q'*) at uniformly like angle of 105 tangents and that the degree of convergence of the jaws being right—to wit, not less than eleven degrees nor more than fifteen degrees, which I have experimentally determined—the wrench will instantly grip the pipe without slipping on forward movement of the handle C in the direction of the arrows and instantly let go without jamming on reversal thereof, whereas in cases of eccentric line arrangement of the teeth, as illustrated 110 by line *k* of Fig. 1 and *k' k'* of diagram Fig. 5, or in cases of combined or successional eccentric lines for the teeth, as illustrated by lines *l* and *m* in Fig. 2 and *l'* and *m'* in dia-

gram Fig. 6, pipe would not be impinged at uniformly like angle of tangents, but would in the cases of the eccentric k and $k' k'$ jam at two or more points and only have one point 5 $D D'$ in common with my invention, and in cases of the combined eccentrics l and m and l' and m' would jam in the narrower space and fail to grip in the wider space.

By reference to Figs. 1, 2, 7, and 8, in 10 which my improved wrench is shown applied to pipes and nuts, it will be seen that by the accurate graduation and differentiation of the teeth I am enabled to present a uniform number thereof for engagement with the 15 pipes or nuts whatever the dimensions thereof may be, if within the range of a given size of wrench, and that by making the perpendicular side of the teeth tangent to the evolute they will engage and sink into the 20 surface of the pipe without "stripping" or "slivering" of their points.

The specific device shown by Figs. 2 and 3 may or may not be employed with the other 25 features of my invention and, as is manifest, might be employed advantageously in wrenches which do not embody the other features of my invention herein disclosed and in either case without departing from the spirit of my invention.

30 The concave recesses $i i$ I make of equal depth and uniform size and equidistant from the pivot in order that when the wrench is thrust against a pipe preparatory to gripping the same any one of the recesses without regard to the size of the pipe will instantly and automatically stride the same without manual adjustment, and I make the surfaces of the recesses smooth or toothless in order that the same as the handle C is moved forward 35 in the direction of the arrow shall with least possible frictional resistance freely slide circumferentially around the pipe p , while the latter is held by a rolling contact with the teeth of the circumscribing jaw A and on reversal of the handle as freely slide off and release the pipe. This construction I specifically claim.

Having described my invention, what I claim as new, and desire to secure by Letters 40 Patent, is—

1. In a wrench of the type described in combination, a rigid arc-shaped fulcrum-jaw, a rigid circumscribing jaw provided with teeth having their respective points ranged 45 upon a true involute line relatively the working surface of said fulcrum-jaw, and a suitable handle.

2. In a wrench of the type described in combination, a rigid arc-shaped fulcrum-jaw, a rigid circumscribing jaw provided with 50 graduated differential teeth having their respective points ranged upon a true involute line relatively the working surface of said fulcrum-jaw, and a suitable handle.

3. In a wrench of the type described in 55 combination, a rigid fulcrum-bearing, a concave-recessed pivoted striding fulcrum-piece mounted in a slot therein, a rigid circumscribing jaw provided with teeth having their respective points ranged upon a true involute 60 line relatively the axis of said striding fulcrum-piece, and a suitable handle.

4. In a wrench of the type described in combination, a rigid fulcrum-bearing, a concave-recessed pivoted striding fulcrum-piece 75 mounted in a slot therein, a rigid circumscribing jaw provided with graduated differential teeth having their respective points ranged upon a true involute line relatively 70 the axis of said striding fulcrum-piece, and a suitable handle.

5. In a wrench of the type described in combination, a handle, a rigid circumscribing toothed jaw, a rigid fulcrum-bearing, and a smooth-surfaced, concave-recessed pivoted 85 striding fulcrum-piece mounted in the latter, said concave recesses being equidistant from the pivot, substantially as and for the purposes shown and described.

6. In a wrench of the type described in 90 combination, a rigid arc-shaped fulcrum-jaw, a rigid circumscribing jaw provided with teeth having their respective points ranged upon a true involute line relatively the working surface of said fulcrum-jaw and with the 95 planes of the perpendicular side of each arranged tangential to the evolute, and a suitable handle.

7. In a wrench of the type described in combination, a rigid arc-shaped fulcrum-jaw, a rigid circumscribing jaw provided with teeth having their respective points ranged upon a true involute line relatively the working surface of said fulcrum-jaw, said involute line having a constant angle of convergence 100 of not less than eleven degrees nor more than fifteen degrees, and a suitable handle.

In testimony whereof I affix my signature in presence of two witnesses.

MASCHIL D. CONVERSE.
